UNITED STATES PATENT OFFICE

DAVID E. EVANS, OF COLUMBUS, OHIO, ASSIGNOR TO THE COLUMBUS DENTAL MANUFACTURING COMPANY, OF COLUMBUS, OHIO, A CORPORATION

CARDING DEVICE FOR ARTIFICIAL TEETH

Application filed December 1, 1930. Serial No. 499,383.

Heretofore artificial teeth have been mounted on a card or the like, formed of cardboard, metal or wood in combination with wax or other penetrable material, or 5 having a coating of such material thereon, the teeth being pressed into the wax and being held thereby on the card. This method of mounting the teeth is not satisfactory in warm weather, the wax becomes too soft and easily 10 soils the teeth, and, in cold weather, it becomes too hard and the teeth do not properly adhere.

Another method employed for supporting or mounting teeth consists of a mount of 15 cardboard, wood or metal, having split metal pins.

Another method consists of a mount having spring metal flanges. These last two 20 methods are unsatisfactory because persons often in removing the teeth from the mount pull the teeth transversely of the mount in removing them, instead of in the plane of the mount, which results in chipping the teeth when they are thus removed.

The object of my invention is to provide 25 a mount or card device for artificial teeth, which is substantially rigid in construction and will not easily bend or break.

A further object of my invention is to provide 30 such a mount which will not soil the teeth.

A further object of my invention is to provide 35 a mount for teeth which will eliminate chipping of the teeth when the teeth are removed from the mount.

In the drawings:

Figure 1 is a front elevation of a mount for 40 artificial teeth embodying my invention.

Figure 2 is a side elevation of the same.

Figure 3 is a front elevation of front member of the mount.

Figure 4 is a top plan view of the tooth 45 engaging element detached.

Figure 5 is a longitudinal sectional view of the front member with the tooth holding ele-

ment attached, and said element being shown in full and dotted lines in applied and partly applied positions.

Figure 6 is a vertical sectional view of 50 Figure 1, with a tooth in place thereon.

Figure 7 is a vertical transverse sectional view of a holding device embodying my invention, adapted to hold another type of tooth.

Figure 8 is a vertical transverse sectional 55 view of another embodiment of my invention.

Figure 9 is a front elevation of my mount shown in Figure 7.

Figure 10 is an end elevation of Figure 9.

Figure 11 is a front elevation of the mount 60 shown in Figure 8.

Figure 12 is a front elevation showing another embodiment of my invention.

Figure 13 is an end elevation of Figure 12.

The reference numeral 15 designates the 65 back plate of my improved carding device for artificial teeth, which may be made of any suitable substantially stiff material, such, for instance, as metal, that will not easily bend or break. This backing is provided at its 70 upper and lower edges with rebent edges 16 disposed on its face side and spaced therefrom to form grooves in which a strip of cardboard 17, or other suitable material, is held to the back 15. This element, which I 75 shall hereinafter designate the "tooth card", is crimped lengthwise to form a groove 18. This groove may be formed by crimping, embossing or many other desired manners. The front wall 19 of the groove is provided with 80 the desired number of slots 20, extending vertically, as clearly shown in Figure 3.

In Figure 4 I have illustrated, in top plan, a lug strip, or ribbon 21, which comprises a 85 comparatively narrow strip of non-metallic material (preferably cardboard or like paper or fairly soft fibrous material) which is of such thickness and width that it lies snugly within the groove 18 and is substantially 90 flush with the plane of the rear face of the

tooth card, as clearly shown in Figure 2. The lug strip 21 is crimped at predetermined points throughout its length, to form lugs 22. For purposes of illustration I have shown but two of these lugs, but it will be understood that any desired number may be formed in the strip. The strip 21 is laid in the groove 18 of the tooth card and the lugs 22 are forced through the slots 20 in the front wall of the groove 18, by any suitable means, as clearly shown in Figure 5. It will be noted, as shown in Figure 5, these lugs 22 after being passed through the slots 20, assume a more or less bulbous shape with a restricted neck 23 at and near the plane of the outer face of the wall 19 of the groove. This shape may be termed "dovetail" for the want of a better term. After the lugs are passed through the slots, the tooth card is mounted in the grooves formed by the flanges 16, and thus firmly secured to the back plate 15, as shown in Figure 2, the lugs being in position to receive and hold teeth on the mount, as shown in Figures 1 and 6.

It will thus be understood that an important feature of my invention consists in providing a lug strip which is formed from cardboard or like sheet fibrous material, from which the lugs are projected by a crimping or other offsetting action, such material having a certain degree of resiliency so that it normally maintains its shape, adapting each lug to yield and contract under pressure and to resume its normal or bulbous shape after the pressure is removed. By this means it will be evident that the lug will yield when the tooth supported thereby is pulled transversely away from it, instead of sliding it off the lug, and thereby permit the tooth to be detached, and, as the cardboard or similar fibrous material used is comparatively soft, and much softer than the porcelain of which the tooth is made, all liability of the edges of the teeth being chipped when they are removed will be avoided. Moreover, the described type of lug strip may be easily and cheaply made and applied for use with great facility.

In Figures 7 and 10 the details of structure of the several parts, such as the plate 15^a, tooth card 17^a having the groove 18^a, lug strip 21^a, lugs 22^a, are substantially the same as hereinbefore described, with the exception that the mount as a whole is bent at an angle to suit a particular and well known type of tooth.

The same is true as to the mount shown in Figures 8 and 11, in which I have designated the metal backing with 15^b having three bends. The tooth card 15^e, shown in these figures, is of the same construction as heretofore described, except that it is shaped to the backing.

In Figures 12 and 13 I show still another embodiment in which the metal backing 15^e has a plurality of grooves 24 formed in it, in

which the lug strip 21^e is seated with the lugs 22^e extending through the slots 20^e of the tooth card 17^e.

It will, of course, be understood that a tooth card embodying my invention may take any form and be shaped flat or with one or more angles, to accommodate a particular type of tooth. The card may also be formed with openings A through which may be displayed a suitable designation as to the mould and shade number of the tooth displayed, as provided in the Moyer Patent No. 1,721,526, of July 23, 1927, and such designation being printed on a strip B.

As will be understood from the above the tooth supporting lugs 22 are characterized by the fact that the lugs being made of a somewhat resilient non-metallic material which is softer and more yielding than the porcelain of the tooth they offer less resistance than the porcelain of the tooth and that, therefore, if one pulls the tooth transversely or at any other angle to the longitudinal axis of the lug, the lug readily distorts and permits the tooth to be removed without any danger of spalling the tooth. As far as I know I am the first to provide such a tooth supporting lug. The teeth have a hole and slot complementary to the lug.

It is to be understood that my invention is adapted for use with any size of card that may be used in association with shipping boxes for teeth, whereby the teeth are held firmly in position during shipment.

What I claim is:

1. A carding device for artificial teeth comprising an oblong rectangular backing plate having flanges along its longitudinal edges, a correspondingly shaped card covering the face of said plate and held in engagement therewith by said flanges, said card being formed at intervals with slots extending transversely thereof, and a tooth retaining strip of wood fiber extending longitudinally between the backing plate and card and doubled at intervals to provide dovetailed yielding tooth receiving and supporting lugs projecting through said slots beyond the face of the card.

2. A carding device for artificial teeth comprising an oblong rectangular backing plate having flanges along its longitudinal edges, a correspondingly shaped card covering the face of said plate and held in engagement therewith by said flanges, said card being formed with a portion displaced from its plane to provide a longitudinally extending boss on its face side extending outward beyond the plane of the flanges, and a corresponding groove in its rear side, said boss being provided at intervals with slots extending transversely thereof, and a tooth retaining strip of wood fibre extending longitudinally between the backing plate and card and doubled at intervals to provide dove-

tailed yielding tooth receiving and supporting lugs projecting through said slots beyond the face of the card.

3. A carding device for artificial teeth comprising a backing, a card secured to the backing, the card and backing being bent to provide tooth engaging surfaces arranged at an angle to each other, one of said surfaces of the card having slots therein, and a tooth retaining strip between said surface and the back doubled at intervals to provide yielding tooth receiving and supporting lugs projecting through said slots beyond the face of the card.

15 In testimony whereof I affix my signature.
DAVID E. EVANS.
